BY *Brooks Walker*

with a pair of openings in laterally spaced relation for free passage of a tape rung therethrough, and edge portions of said rung receiving openings intersecting laterally spaced edge portions of said lift cord receiving opening and providing therebetween a freely flexible tongue, and the free end of said tongue defining a marginal portion of said lift cord receiving opening.

2. The structure according to claim 1 wherein said cord receiving opening is elongated transversely of the slat, and said tape rung receiving openings are elongated longitudinally of said slat and spaced apart a distance substantially equal to the length of said cord receiving opening.

3. The structure according to claim 1 wherein said slat is provided with a second pair of openings in laterally spaced relation for the free passage of a tape rung therethrough, and said pairs of openings being disposed on opposite sides of said lift cord receiving opening and intersecting spaced edge portions of said latter opening.

4. The structure according to claim 1 wherein said slat is also provided with a second pair of tape rung receiving openings, and said second pair of openings being longitudinally spaced from the first mentioned pair of openings a distance substantially equal to the width of said lift cord receiving opening and intersecting edge portions thereof.

5. A Venetian blind slat provided with a transversely elongated lift cord receiving opening, said slat being further provided with a pair of longitudinally elongated laterally spaced cut-outs providing openings for free passage of a tape rung therethrough, the adjacent edges of said cut-outs intersecting the adjacent edge of said cord receiving opening thereby providing a freely flexible tongue for engaging said rung intermediate the openings through which the rung passes, and

the free end of said tongue defining said adjacent edge of the cord receiving opening.

6. The structure according to claim 5, together with a second pair of longitudinally elongated laterally spaced cut-outs on the opposite side of the cord receiving opening and providing additional openings for free passage of a tape rung therethrough, the adjacent edges of said second pair of cut-outs also intersecting an edge of said cord receiving opening thereby providing a second freely flexible tongue, and the free ends of said tongue defining opposed edges of said cord receiving opening.

7. A Venetian blind slat provided with a transversely elongated rectangular lift cord receiving opening, a pair of laterally spaced longitudinally elongated rectangular openings at each side of said cord receiving opening for free passage of a tape rung therethrough, adjacent edges of the rung receiving openings of both pairs thereof intersecting the opposed corners of the lift cord receiving opening, thereby providing a pair of freely flexible tongues with the cord receiving opening disposed between the free ends thereof, and the rung receiving openings of the respective pairs disposed at opposite sides thereof, and a pair of rectangular slat portions free of the tongues normally closing communication between opposite ends of the lift cord receiving opening and adjacent ends of the rung receiving openings.

E. J. HUNTER.
